UNITED STATES PATENT OFFICE.

FLOYD G. WITHROW, OF GRAND RAPIDS, MICHIGAN.

PRIMING-ROD ANTIRATTLER.

Application filed July 27, 1925. Serial No. 46,381.

To all whom it may concern:

Be it known that I, FLOYD G. WITHROW, a citizen of the United States of America, residing at Grand Rapids, in the county of Kent and State of Michigan, have invented certain new and useful Improvements in Priming-Rod Antirattlers; and I do hereby declare the following to be a full, clear, and exact description of the invention, such as will enable others skilled in the art to which it appertains to make and use the same.

This invention relates to a novel construction of anti-rattler adapted for application, in Ford automobiles, to the rod which is used to adjust the needle valve and also to the means used for operating the choke in the carburetor in order to obtain a richer mixture, particularly on starting the engine of the automobile. The anti-rattler which I have made is constructed from a single piece of wire and engages both said needle rod and said choke operating means, holding the same against aimless movement and stopping rattling noises ordinarily produced on account of vibrations imparted to the machine from road shocks in driving the same.

A primary object and purpose of the invention is to produce a simple and very effective device of this character from a single piece of spring wire and which can be made at low cost, which is easily applied and which, when applied, serves to effectively eliminate said rattling noises mentioned. The device by means of which these ends, as well as others not at this time particularly stated, are attained is illustrated in the accompanying drawing, in which,

Fig. 1 is a front elevation of the front side of the dash of the automobile showing the anti-rattling device in connection with the needle valve adjusting rod and the choke operating means.

Fig. 2 is a side elevation thereof, the dash being shown in vertical section, and

Fig. 3 is a perspective view of the anti-rattler.

Like reference characters refer to like parts in the different figures of the drawing. In the construction of the Ford automobile a vertical dash 1 of sheet metal is provided on the front side of which back of and above the engine a bracket 2 is mounted carrying a pivot pin 3, on which a bell crank lever is mounted for turning movement, the same

including an upwardly and forwardly extending arm 4 and a downwardly and forwardly extending arm 5, suitable connections being made between the lower end of the arm 5 and the choke valve of the carburetor. A rod 6 is pivotally connected at its lower end to the end of the arm 4 and extends upwardly and to the rear through a slot in the dash 1, terminating in a knob 7 which may be grasped by the operator of the automobile so as to pull the rod to the rear and in this way close or partially close the choke valve.

A short distance from the choke operating means described the rod for adjusting the needle rod valve is located. Said rod 8 at its free end has a right angle bend 9 which serves as a handle whereby the rod may be turned about its axis. The rod 8 extends downwardly and forwardly through a slot in the dash 1 to and has connection with the carburetor needle valve as is well understood by all familiar with Ford automobile construction.

The rods 6 and 8 passing through the slots in the dash 1 are not held in any position except as prescribed by the boundaries of the slots and in the operation of the automobile may vibrate and strike against the sides of said slots, this producing rattling noises. The device which I have made for application to these rods is shown best in Fig. 3. It comprises a vertical end section 10 which, at its upper end, is bent at right angles to make a short horizontal section 11 and thence extended downwardly making the section 12 which is nearly parallel to though diverging slightly from the section 10, sections 10, 11 and 12 being substantially inverted U-shaped. In the section 12 between its ends an off-set portion 13 is made as shown. The lower end of the section 12 extends a short distance below the lower end of the section 10 and is formed into a spring coil 14, the other end of the coil being thence extended outwardly and somewhat upwardly as indicated at 15 for a short distance and formed into a loop comprising a side 16, bend 17 and a second side 18, the loop being turned substantially at right angles to the part 15. The side 18 of the loop is continued a distance beyond the end of the side 16 and thence bent back upon itself in a curve of relatively large radius, shown at

100
105

19, and thence extended nearly parallel to the side 18 in a side 20 which terminates in a right angle bent hook 21.

This device when applied to the rods 6 and 8, the dash 1 and the arm 4 of the bell crank lever, is located with the inverted U-shaped portion formed by sections 10, 11 and 12 lying snugly against the front of the dash with the section 12 bearing against a side of the rod 6. The coil 14 is also located flat against the front side of the dash and the section 15 extends upwardly between the dash and the rod 8, said rod being received in the bend of the loop formed by the sides 16 and 18 and the bend 17 connecting the same. In applying the device in this manner the coil 14 is placed under tension by reason of the fact that the section 15 must be bent toward the section 12, the coil 14 located between said sections 12 and 15 being stressed. The terminal portions 20 and 21 of said device are engaged with and hooked over the upper edge of the arm 4, said arm 4 being subjected to the spring tension of said device as it is necessary to bend the arm 20 somewhat toward the arm 18 in making this connection with the arm 4. The section 12 of the device is pressed with spring tension against the side of the rod 6 forcing the same over against one side of the dash slot through which it passes, and the rod 8 is acted upon by said device forcing the same over against the opposite side of the dash slot through which it passes. The bell crank lever is engaged by the end of said device with a yielding spring tension so that both rods 6 and 8 and the bell crank lever are frictionally held in place and do not vibrate and rattle during the operation of the machine. In operating the choke, that is, by pulling back on the knob 7, it is evident that the part 20 is moved with the movement of the bell crank arm 4 but the spring character of the material from which the device is made readily permits this, while a further function is served by the device in that it automatically returns the choke operating means to normal position as soon as free to do so. This is of value, irrespective of the fact that the choke valve associated with the carburetor may be spring actuated itself, as such spring on the choke valve is susceptible to breakage which occurs quite frequently; and if such breakage of the choke valve occurs the device illustrated and described herein serves to move the choke valve to its normal position and hold the same therein except when manually operated to a different position.

The simplicity of the construction of the anti-rattling device shown and described is a valuable feature of the invention inasmuch as it can be produced at very low cost. The installation is exceptionally easy and simple, requiring no tools and the spring tension de-

veloped in the anti-rattling device when it is installed precludes its disconnection from the parts with which it is associated. The invention is defined in the appended claims and is to be considered as comprehensive of all forms of structure coming within their scope.

I claim:

1. In combination with a vertically disposed automobile dash, a needle valve operating rod extending downwardly and forwardly through said dash, and a choke valve operating means mounted on the front side of said dash and comprising a pivotally mounted bell crank lever and an operating rod therefor extending upwardly and to the rear through the dash, of an anti-rattling device disposed against the front side of the dash and having parts engaging against said rods and bell crank lever with yielding spring tension to hold the same against aimless movement.

2. In combination with the vertically disposed dash of an automobile, a needle valve operating rod passing downwardly and forwardly through said dash, said dash having a slot for the passage of the rod, and a choke valve operating means mounted on the front side of the dash and including an operating rod extending downwardly and forwardly through the dash which is provided with a second slot for the passage of said second rod, of an anti-rattling device mounted in front of the dash and having parts engaging against both rods, said parts engaging against the rod being under spring tension to thereby force each rod against a side of its slot and prevent rattling of the rods.

3. In combination with a vertically disposed automobile dash having two slots cut therein, two rods extending downwardly and forwardly through said slots in the dash, an anti-rattling device formed from a single piece of spring wire located between the rods and engaging against the same on their adjacent sides, said device between its points of engagement with the rods being formed with a spring coil whereby the parts of the device engaging the rods are pressed against said rod with spring tension, substantially as described.

4. In combination with an automobile dash having two slots cut therethrough, of two rods extending downwardly and forwardly one through each slot, a bell crank lever pivotally mounted at the front side of the dash with which the lower end of one of said rods is connected, an anti-rattling device located between the rods including an intermediate spring section from which arms extend outwardly at an angle to each other said arms being adapted to be bent toward each other to pass between the rods so that one engages against one side of one rod and the other engages against the adjacent side

of the other rod, one of said arms being continued and formed into a spring loop having a terminal end portion under spring tension engaging with an arm of the bell

5 crank lever.

5. An anti-rattler for the purposes described comprising, an intermediate spring coil having the end portions thereof extended at an angle to each other, one of said end 10 portions at its end being formed into a loop disposed substantially at right angles to said end portion, said loop being continued and formed into a return bend and terminating in a straight section having a right angle 15 hook at its end, substantially as described.

6. An anti-rattler for the purposes described formed from a single piece of spring wire and comprising a spring coil having end portions extending from the coil at an angle to each other, one of said end portions 20 being formed into inverted U-shape and the other turned substantially at right angles and formed into a loop and thence extended and formed with a return bend and terminating in a spring section having a right 25 angle hook at its extreme end, substantially as described.

In testimony whereof I affix my signature.

FLOYD G. WITHROW.
